Application filed October 13, 1898. Serial No. 693,458. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, which represents a plan view of a portion of a strip of wall-paper embodying the features of my design.
